United States Patent Office.

FREDRICK FISCHBECK, OF CHICAGO, ILLINOIS.

Letters Patent No. 86,742, dated February 9, 1869.

IMPROVED METALLIC PROTECTOR OR SHIELD FOR TRAVELLING-BAGS.

The Schedule referred to in these Letters Patent and making part of the same.

To all whom it may concern:

Be it known that I, FREDRICK FISCHBECK, of the city of Chicago, in the county of Cook, and State of Illinois, have made certain new and useful Improvements in Travelling-Bags and similar articles; and I do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use my invention, I will proceed to describe it, remarking that it relates to travelling-bags, and consists in the construction of a new useful metallic protector, or corner-piece, for attachment to these bags, or similar articles, to shield and protect the hinge or joint of the bag from injury, as well as to furnish additional resting-points when it is set down.

In the drawings—

Figure 1 is a plan view of the frame of travelling-bag, showing the hinge, with my protector, entire, on one corner, and the protector, in section, on the other, as attached; and

Figure 2 is a plan view of my protector detached.

The jaws of travelling-bag frames being hinged at their ends, and near the bottom or under side of the bag, frequently have these hinges broken or injured from careless handling, or other causes, and are also liable to be broken when the bag is allowed to fall violently on its under or bottom side.

To strengthen these corners, protect the hinges, and thus securely guard against injuries of this kind, is the object of my invention.

To accomplish this, I cast, out of iron, or other suitable metal, an L-shaped corner-piece, F, with flanges, a and b, and a knob or foot, g, as clearly shown in fig. 1. This I call my "protector" for the hinges of the bag-frames.

It may be made of any size desired, for the purpose of fitting the articles to which it is to be attached.

This is done, as clearly shown in fig. 1, in which is represented a bag-frame, E, with its jaws A and B hinged at C, and connected by a suitable cross-piece, D, forming a part of one of them, if desired, or in any of the usual ways, and the protector F attached.

I attach it by means of rivets, d, which pass through holes, c, in the protector, and in the frame E, made for that purpose, as shown in fig. 1, and with its knob, or foot, g, on the under side, and the flanges a and b extending over the rim of the frame, as shown in the same figure.

As this protector is made of cast-metal, its solidity and strength securely guard the hinges from injury, and its foot, or knob, furnishes a substantial foot for the bag to rest upon.

Having thus described my invention,

What I claim, is—

The cast-metallic protector F, constructed and attached to travelling-bags, or similar articles, substantially as herein described and for the purposes set forth.

FREDRICK FISCHBECK.
